US0D1055308S

(12) **United States Design Patent** (10) Patent No.: **US D1,055,308 S**
(45) Date of Patent: ** Dec. 24, 2024

(54) **ENVIRONMENTAL CONTROL MODULE**

(71) Applicant: **SURGIBOX INC.**, Cambridge, MA (US)

(72) Inventors: **Sashidhar Jonnalagedda**, Vernier (CH); **Mike Horia Mihail Teodorescu**, Cambridge, MA (US); **Atif Mohammad Rakin**, Storrs, CT (US)

(73) Assignee: **SurgiBox Inc.**, Cambridge, MA (US)

(**) Term: **15 Years**

(21) Appl. No.: **29/814,294**

(22) Filed: **Nov. 4, 2021**

(51) LOC (14) Cl. **23-04**

(52) U.S. Cl.

USPC **D23/364**; D10/96; D24/232

(58) **Field of Classification Search**

USPC D24/107, 216, 231, 232, 234; D10/49, D10/85, 96; D23/332, 355, 364, 365, D23/370, 383, 421, 499

CPC . F24F 3/14; B05C 11/00; B65D 37/00; B65D 35/22

(57) **CLAIM**

The ornamental design for an environmental control module, as shown and described.

DESCRIPTION

FIG. 1 is a perspective view.

FIG. 2 is a top view.

FIG. 3 is a bottom view.

FIG. 4 is a right side view.

FIG. 5 is a left side view.

FIG. 6 is a front side view; and,

FIG. 7 is a rear side view.

In the drawings, the equal-length broken lines depict portions of the environmental control module that form no part of the claimed design.

1 Claim, 7 Drawing Sheets
